UNITED STATES PATENT OFFICE.

CHARLES HURBERT MELVILLE AND THOMAS WALTER BROWN, OF CHATTANOOGA, TENNESSEE.

ROTARY ENGINE.

SPECIFICATION forming part of Letters Patent No. 310,531, dated January 6, 1885.

Application filed March 7, 1884. (No model.)

To all whom it may concern:

Be it known that we, CHARLES H. MELVILLE and THOMAS W. BROWN, both of Chattanooga, in the county of Hamilton and State of Tennessee, have invented a new and Improved 5 Rotary Engine, of which the following is a full, clear, and exact description.

Our invention consists of an improved contrivance of a radially-operating abutment with 10 an eccentric revolving steam-actuated hub for utilizing steam-pressure to maintain steam-tight contact of the abutment with the said hub; and our invention also consists of an improved contrivance for an automatic variable cut-off valve for regulating the supply of 15 steam to the engine, all as hereinafter fully described.

Reference is to be had to the accompanying drawings, forming part of this specification, 20 in which similar letters of reference indicate corresponding parts in all the figures.

Figure 1 is a sectional elevation of our improved engine on the line of the shaft. Fig. 2 is a detail of the arrangement of the abutment, partly in section. Fig. 3 is a sectional elevation of the engine on the line $x'x'$ of Fig.

1. Fig. 4 is a perspective view of the abutment. Fig. 5 is a perspective view of the steam-valve; and Fig. 6 is a detail of the case, 30 showing the arrangement of the abutment.

Within a cylindrical case of ordinary form for rotary engines, consisting of rim a and heads a' , we arrange the cylindrical drum or hub b , fitting it eccentrically to the shaft c , so 35 that its highest point will work close to the inner periphery of the rim of the case, and at this point we fit a suitable packing, e , to prevent steam from leaking past it. At the top of the rim of the case or in any other ap- 40 proved part we arrange a radially-reciprocating abutment, d , to separate the inlet-passage f for steam from the exhaust g , preferably arranging said abutment in the steamway f , which we construct in suitable size and form 45 for the purpose, providing, also, a suitable radial extension-chest, h , of the case for the purpose, making said chest wider than the thickness of the drum b , for enabling the abutment to be made wider in order that its ends 50 may have an extension, i , reaching beyond

the edge j , that rests on the face of the drum b , and that said ends may work in radial grooves k , which we form in the sides of the case to form supports for the abutment, to resist the steam-pressure and to pack more effectually 55 against waste of steam past the abutment than would result if the abutment were of the same width of the drum and worked between the plane sides of the case.

Over the abutment-case h we arrange a 60 steam-cylinder, l , with a piston, m , in it, that is connected by its rod n with the abutment d , and having a steam-passage, o , leading into it above the piston from the abutment-chest h , for pressing the abutment down on the face of 65 the drum to insure a tight joint, to prevent the steam from leaking past the abutment to the exhaust. The cylinder l is open from the under side of the piston to the exhaust side of the abutment d through passage p , for the 70 escape of steam that may leak past the piston, and which would, if confined, balance the pressure on the piston and prevent the desired effect. The rod n is packed with a stuffing-box, b' , in the lower head of the cylinder. 75

For regulating the steam admitted to the cylinder we use a rotary valve, q , of cylindrical form in a corresponding valve-case, s , from which the port t discharges into the steamway 80 f of the abutment-chest h , said port having considerable length along the valve-case, as shown in dotted lines in Fig. 1. The steamway through the valve is formed between the straight edge u of the valve, extending the 85 whole length of the port t , so as to open along the whole length of the port at once, and the spiral line v , beginning at the line u at the back end of the valve and terminating at w on the front end, between which point and 90 line u about a quarter of the full size of the cylinder remains. This spiral line v forms the cut-off, and its effect is made variable by the arrangement of the valve to shift lengthwise in the valve-case, so that said line will 95 cross the port earlier or later, according as the valve is shifted one way or the other, which is effected by the governor-levers x , pivoted to the arms y of the pulley z , fitted on the shaft a' of the valve, said arms being suitably con- 100

ected with the hub b' of said shaft, and the pulley z being geared with the main shaft c by a driving chain-belt d' ; or it may be other approved means, by which the valve will be 5 rotated synchronously with the drum b . With this valve steam may be cut off from three-quarters of the revolution of the drum to as much less as may be desired, said valve being capable of shifting so far along the port as to 10 open it for but a very short portion of the revolution, if the cylindrical portion of the valve be made about as long as the port, as it may be, if desired.

Having thus described our invention, we 15 claim as new and desire to secure by Letters Patent—

1. The combination of the steam-cylinder l and piston m with the radially-sliding abutment d and eccentric drum b , arranged in a 20 steam-cylinder a a' , said cylinder l being open to the live steam above the piston and open to the exhaust below said piston, substantially as described.

2. The radially-reciprocating abutment d , arranged in the abutment-chest h , wider than 25 the drum b , and fitted in the radial grooves k of the sides of the case, and having extensions i reaching past the face of the drum, each side of it, and in said groove k , substantially as described.

3. The rotary cylindrical steam-valve q , having straight steam-inlet line u and the spiral cut-off line v , and being arranged to shift lengthwise automatically by the action of the governor for automatically varying the cut-off 35 of the steam at the port t , in combination with the abutment d , all constructed and arranged substantially as described.
